UNITED STATES PATENT OFFICE

JOHN D. ELDER, OF CATONSVILLE, MARYLAND, ASSIGNOR TO CROWN CORK & SEAL COMPANY, INC., OF NEW YORK, N. Y., A CORPORATION OF NEW YORK

DRYING OVEN UNIT

Application filed December 11, 1928. Serial No. 325,953.

My invention relates to drying oven units, and more particularly to a unit of a type wherein the oven has travelling racks therein, and has associated therewith a printing or other machine for applying a decoration in ink or coating of other material to metallic or other sheets, and immediately delivering such sheets to said racks.

Drying ovens embodied in units of the type to which my invention relates contain a large number of racks for supporting sheets edgewise in fairly close, but non-contacting, relation with each other, while said racks are travelling through the oven. The time interval between the feeding of sheets to said racks and their delivery from the oven is such as to ensure a sufficiently complete drying or oxidation of material applied to a surface or surfaces of said sheets to permit the handling of the sheets, without likelihood of scratching or smutting the surface of the sheets, immediately following their delivery from the drying oven.

When an elevated temperature is employed in such ovens, it is desirable, to avoid spoilage or wastage, that the racks in the oven travel substantially continuously, and that the oven be operated for a sufficient time following the shutting down of the associated printing or other machine, to complete the drying operation upon all work delivered to the oven carrier racks. While an oven ordinarily is operated substantially continuously, it is commonly necessary to stop the associated printing or other machine a number of times during a run thereof.

While, with the proper adjustment of mechanisms in the printing or other machine with relation to the actuating means for the carriers for the racks in the oven, the printing or other machine and the oven carriers may be continuously operated with a proper timing in relation to each other, this adjustment is immediately lost with the stoppage or reversal of the printing or other machine. Prior to my invention, the adjustment of such mechanisms preparatory to, or during, a run of the printing or other machine to establish a proper timing in the relative operation of these mechanisms, required consid-

erable time, and necessitated careful work by the operatives in order to avoid collision between the sheets delivered to the drying oven and the edges of the racks having movement through said oven, and a resultant distortion of the delivered sheets, or scratching or smutting of the fresh coating material thereon.

To avoid delays in the operation of the printing or other machine, due to the adjustment of the actuating mechanism therefore in relation to the actuating mechanism for the carrier of an associated oven, and possible inaccuracies in the making of such adjustment, and permit a continuing operation of the oven, notwithstanding the stoppage of the printing or other machine, I provide an actuating mechanism for imparting travel to the oven racks to which power is transmitted from the actuating mechanism for the printing or other machine, which mechanism not only brings a rack into position to receive a decorated sheet from the delivery mechanism of the printing or other machine at a certain point of each cycle of operations of said printing or other machine, but, following the operation of the oven after the stoppage of the printing or the machine, automatically controls the application of power to the oven carrier by the actuating mechanism for the printing or other machine until the relation of parts in such machine and the oven racks is such that when a decorated sheet is to be delivered to a rack, a rack is properly positioned to receive it without danger of collision therewith or with a preceding rack.

The utilization of a single source of power for driving both the printing or other machine and the oven racks, and the employment of a power transmission mechanism having the above characteristics, not only results in that automatic adjustment of the two mechanisms in relation to each other above referred to, but at all times when both mechanisms are functioning, synchronizes the operation of the actuating mechanisms of the printing or other machine and of the rack carriers so as to avoid the development or accumulation of error even during a

protracted run of the unit, since any variation in the speed of the actuating mechanism for the printing or other machine will be accompanied by a similar variation, in the 5 proper ratio, of the rack carrier actuating mechanism.

In conjunction with the power transmission mechanism, for connecting the actuating mechanism for the printing or other machine and the rack carrier actuating mechanism, I provide an independent source of power capable of imparting movement to the rack carrier actuating mechanism independently of the source of power operative upon 10 the printing or other machine, so that upon the interruption of the power to said printing or other machine, a continuing travel may be imparted to the oven racks by said independent source of power.

20 The construction and arrangement of parts is such, that when power is being applied to said printing or other machine, and said power transmission mechanism is operative upon the rack carrier actuating means, the 25 racks will be normally "in step" with the printing or other machine, and irrespective of the position of the racks, upon power being initially applied to the rack carrier through the transmission mechanism when 30 starting said machine or mechanism, any deviation from a proper normal relative position of said machine parts and said racks will be compensated for whatever the extent of this deviation may be. Furthermore, in 35 the embodiment of the invention herein shown and described, the construction and arrangement of parts is such that the automatic adjustment will be accomplished at some point of a single cycle of operations of 40 the printing or other machine, so that any loss of adjustment from any cause whatever will be immediately corrected during a single cycle of operations of said machine.

The independent source of power may be 45 so connected with the oven rack actuating mechanism as to be automatically disconnected therefrom upon the application of power to said mechanism through the transmission mechanism, although, as will more 50 fully appear hereinafter, this is merely a preferable, and not an essential, characteristic of the structure of my invention.

55 The invention consists primarily in a drying oven unit embodying therein the combination with a printing or other machine, an oven carrier having a sequence of racks, actuating mechanisms operative respectively upon said machine and said carrier, and a source of power common to both of said actuating mechanisms, of power transmitting means between said mechanisms, embodying 60 therein an automatically acting clutch mechanism permitting the operation of said carrier actuating mechanism independently of said transmitting mechanism, and means

whereby said clutch is operative to transmit power only when said machine and said carrier are in normally operative relative positions, and means for applying power to said carrier actuating mechanism independently 70 of said main source of power; and in such other novel features of construction and combination of parts, as are hereinafter set forth and described, and more particularly pointed out in the claims hereto appended. 75

Referring to the drawings,

Fig. 1 is a side elevation of a unit embodying the invention, only a fragmentary part 80 of the machine feeding mechanism and of the oven proper being shown;

Fig. 2 is a side view of the clutch mechanism shown partly in section and partly broken away;

Fig. 3 is a top view of Fig. 2; and

Fig. 4 is a detailed view of the mechanism 85 for applying power to the oven carrier actuating mechanism independently of the printing or other machine actuating mechanism.

Like numerals refer to like parts throughout the several views.

In the embodiment of the invention shown in the drawings, it is illustrated in connection with a drying oven unit including an ordinary tin plate drying oven having associated therewith an ordinary planographic printing press for applying decorative designs to tin plates. A fragmentary portion of the 95 drying oven is shown at 10, the printing press is shown at 11, and the printing couple of said press at 12-13.

Drying ovens of the type above referred to, are provided with a carrier consisting of sprocket chains having a large number of racks thereon, said carrier having travel imparted thereto at fairly low speed through 105 the oven by means of sprocket wheels about which the chains pass. A fragmentary portion of the carrier and sprocket mechanism is shown at 14-15, and a number of racks 16 at 110 the point where the chain 14 passes about the sprocket wheel 15 at one end of the oven are also shown. A further detailed description of the oven is unnecessary since the construction and mode of operation of such ovens are old and well known in the art, and the present invention relates more particularly to the 115 means for actuating the carrier and not to the oven structure per se.

As shown in Fig. 1 of the drawings, the curvature of the carrier, where the chain 14 passes about the sprocket wheel 15, will position the various racks 16 radially of the axis of said wheel, the resultant divergence of 120 these racks toward the outer ends thereof affording clearance facilitating the feeding of 125 a sheet in relation to each rack.

The printing or other machine 11 is provided with ordinary delivery tapes 17, the discharge end of which is adjacent the path 130 of movement of the outer ends of the various

racks 16 so as to permit a tin plate upon said delivery tapes to be fed directly to a rack 16. This general construction and arrangement of parts is old and well known in the art, the practice prior to my invention being to provide a source of power acting simultaneously upon the mechanism 11 and the sprocket wheel 15, and a manually operable clutch by which said source could be disconnected from said sprocket wheel. A separate source of power was also provided for the sprocket wheel which could be used when said clutch was released. With this condition, as heretofore stated, it was necessary to manually adjust or regulate the relative position of the printing couple 12—13 of the machine 11, and of the racks 16 after each stoppage of the machine 11, so that during a run of said machine, the timing of the positioning of succeeding racks in relation to the delivery tapes 17 would be in accord with the delivery of sheets as a result of the operation of the machine 11. This adjustment or regulation required considerable time and the exercise of considerable skill to ensure the proper positioning of the various parts.

As shown in the drawings, the machine 11 is driven by means of power supplied from a motor 18, this power being applied to the main power shaft 19 of the actuating mechanism for the machine and the gear train connecting said power shaft with the printing couple.

The carrier 14 of the oven proper is provided with its own actuating mechanism by which its speed of travel may be so controlled as to position a rack 16 in the operative relation to the delivery belt 17 with each cycle of operations of the machine 11 during the normal operation of the unit. Since with each rotation of the sprocket wheel 15 driving said carrier, a number of racks 16 will be brought into and removed from their operative position in relation to the tapes 17, the actuating mechanism for said carrier must include a speed reducing mechanism which, in the form of the invention shown, consists of a worm wheel 20 and worm shaft 21 and other speed reducing means, so that the ratio of speed of the sprocket wheels, as compared with that of the printing couple of the machine 11, is such that only one rack 16 will be brought into the operative relation to said delivery tapes 17, and moved therefrom, with each revolution of the printing couple 12—13. It will be noted that the speed ratio of the carrier actuating mechanism is based upon that of the printing couple and not of the main power shaft of the machine 11. This is because of the speed reducing connection between the main power shaft and said printing couple. The establishment of this ratio was old and well known prior to my invention.

My present invention includes a power transmission mechanism by which, when said

machine and said carrier are in normally operative relative positions, power from the same source, the motor 18, will be applied simultaneously to the actuating mechanism for the machine 11 and to the oven carrier 79 actuating mechanism, which transmission mechanism includes therein, means permitting power from an independent source to be applied to the oven carrier actuating mechanism upon the interruption of the application of power by the motor 18. 75

For the purposes of the present specification, the actuating mechanism for the oven carriers will be considered as including the sprocket wheel 15, the worm wheel and shaft 20—21 or other speed reducing gearing, the driven shaft 22 of an automatically acting clutch mechanism embodied in a sort of differential gearing, and gears 23 and 24 connecting the shaft 22 with the shaft 21. The actuating mechanism for the machine 11 will be considered as the main power shaft 19 and the gearing connecting same with the printing couple 12—13. 85

Driven from the actuating mechanism for the machine 11, in any desired manner, as by the chain and sprocket mechanism 25 and the gears 23 and 27, is the driving shaft 28 of the transmission mechanism, one end of which shaft is suitably mounted adjacent said gears 26 and 27, and the other end of which is mounted in a suitable bracket 29. 90

Carried by and rotatable with the shaft 28 is the driving member of an automatically acting clutch mechanism consisting of a frame 30, having idly mounted therein a large bevelled gear 31. In mesh with said gear 31 is a small bevelled gear 32, carried by the driven shaft 22 forming a part of the oven carrier actuating mechanism, which shaft 22, 105 adjacent said gear, is mounted in a suitable bracket 33 and also in one end of the frame 30. 100

Carried by the gear 31 is a clutch plate 34 having a single tooth 35 thereon. Mounted upon the frame 30 is a spring pressed dog or pawl 36, co-operating with the clutch plate 34 and its tooth 35. This pawl 36 permits rotation of the gear 31 in one direction, and prevents rotation thereof in the opposite direction. Hence, when the pawl or dog 36 is 110 engaged with the tooth 35, the only movement of the gear 31 will be a planetary movement about the axis of the shafts 22 and 28, and rotary movement will be transmitted from the driving shaft 28 to said driven 115 shaft 22. 120

With the stoppage of the shaft 28, however, planetary movement of the gear 31 ceases, and with a continued rotation of the shaft 22, said gear will be turned about its 125 own axis by the gear 32, thus disengaging the tooth 35 from the pawl or dog 36 to an extent determined by the quantity of rotary movement of said gear 31. The effect of this will be more fully described hereinafter. 130

Consequently, when the pawl 36 is engaged with the tooth 35, or the clutch is set, the frame 30 may be rotated in unison with the shaft 22, or said shaft 22 may, when required, be rotated independently of said frame and automatically disengage the tooth 35 from the pawl 36 to release said clutch.

The construction heretofore described, affords means permitting rotation of the shaft 22 and the operation of the oven carrier actuating mechanism independently of its actuation by said transmitting mechanism, and the clutch plate 34 and pawl or dog 36 co-operating with the tooth 35 of said clutch plate affords means whereby the clutch is made operative only to transmit power when said machine and said carrier are in normally operative relative positions. This also will be more fully described hereinafter.

In order to ensure a continued operation of the actuating mechanism for the oven carrier, I provide a separate source of power, preferably consisting of a motor 37 connected by a speed reducing mechanism 38 with the driven shaft 22. Preferably, this connection is by means of an ordinary ball clutch mechanism 39, as shown in Fig. 4, so that there will be an automatic disconnection of the shaft 22 from the motor 37 when power is applied to said shaft by the driving shaft 28, it being understood that the speed of drive of the driven shaft 22 by the motor 37 when the clutch 39 is used is lower than the speed of drive of the driving shaft 28.

Printing machines are commonly equipped with automatic feeders, and a fragmentary portion of such a feeder is illustrated at 40 in Fig. 1. In order to secure uniformity in timing throughout the unit, I preferably transmit power to the feeding mechanism from the shaft 19, through the gear 26 by means of the shaft 41, having gears enmeshed respectively with the gear 26 and a gear connected with the main power shaft of the feeder. This arrangement, however, is a mere matter of convenience.

The operation of the herein described unit is substantially as follows:—

In describing the operation of an oven unit embodying the invention, certain arbitrary figures will be selected.

Let it be assumed that the printing couple 12—13 has a speed of 48 R. P. M.; that the sprocket wheel 15 has 24 teeth; that the ratio of the chain and sprocket mechanism 25 is such as to rotate the driving shaft 28 of the transmission mechanism at a speed ratio of four to one in comparison with the speed of the members 12—13 of the printing couple, or 192 R. P. M.; that the speed ratio of the gearing 23—24 is as one to two, and that the ratio of the worm 21 and gear 20 is as one to forty-eight.

With the conditions above described, the sprocket wheel 15 will be turned one-twenty-

fourth of a revolution with each revolution of the members 12—13 of the printing couple, or have two R. P. M., so that during each minute, forty-eight racks will be brought into, and moved out of, the operative relation to the delivery tapes 17. Hence, when the pawl 36 is engaged with the tooth 35 so as to cause a normal operation of the unit, the carrier racks will be absolutely in step with the printing couple at all times and at every point of the cycle of operations of said couple.

Upon the interruption of power to the motor 18, however, it is necessary to apply power to the carrier actuating mechanism from the motor 37, and as a matter of convenience, the power of this motor is applied through the clutch mechanism 39 to the shaft 22, for which reason this shaft is herein considered as a part of the actuating mechanism for the oven carrier.

When the motor 37 is operating, it is obvious that the movement of the racks is out of step with the printing couple, which is at rest, since, while power is being applied to the driven shaft 22, the gear 32 is being rotated and will impart movement to the gear 31 in the direction shown by the arrow, Fig. 2, thus releasing the clutch because of movement of the tooth 35 of the clutch plate 34 away from the dog or pawl 36, the frame 30 being stationary.

The ratio of the gears 31 and 32 is as four to one, which is the same ratio as that existing between the speed of the printing couple and the shaft 28. Consequently, the tooth 35 can be disengaged from the pawl or dog 36 only during a period corresponding with substantially one full rotation or cycle of operations of the printing couple, and during this time, only a single rack may be moved into and out of the proper relation to the tapes 17.

In assembling the transmitting mechanism, the printing couple 12—13 and the oven carrier 14 are so set that with a normal operation of the unit by the main actuating mechanism, the tapes 17 will deliver a printed or otherwise decorated or coated sheet to a rack 16, and a rack 16 will be so positioned as to properly receive this sheet upon the completion of each cycle of operations. When the parts are in this position, the automatically acting clutch mechanism or differential gearing is incorporated in the transmission mechanism with the gear 31 meshed with the gear 32 and the tooth 35 engaged with the pawl or dog 36. With the parts in this position, upon the application of power to the motor 18, the printing or other machine 11 and the carrier 14 will be simultaneously actuated, and by reason of the establishment of the proper speed ratio between the printing couple 12—13 and the carrier 14, the racks 16 will be successively brought into the operative relation to the delivery tapes 17, the timing of their positioning being synchro-

nized with the operation of the printing machine 11, and this synchronization will not be disturbed by any variation in the speed of operation of the printing machine nor during any part of a full cycle of operations.

Upon the assembly of a drying oven unit as above described, a proper relation of parts is established, but the difficulty is not to establish this relation of parts, but to reestablish it when synchronization in the operation of the two mechanisms is lost as a result of the actuation, stoppage or reversal of the machine 11, either during the makeready of the printing or other machine 11, or when servicing or repairs are required during a run of the machine.

After a drying oven unit has once been put into service, as heretofore stated, it is essential to continue the operation of the carrier 14 after the stoppage of the machine 11, so that during the makeready of any press, when resuming a run or starting a fresh run, the carrier 14 may be so positioned, if power were applied to the carrier actuating mechanism simultaneously with the application of power to the actuating mechanism for the printing or other machine 11, the various racks would be actuated out of step with the printing couple 12-13 and there would be constant collision between the delivered sheets and the racks.

During the makeready of the press, this condition ordinarily exists, and prior to my invention, when starting up a unit in the morning and in the afternoon, it was necessary to manually adjust the mechanism 11 and the carriers 14 so as to establish a proper relation of these parts to permit the beginning of a run. The same conditions were present following any stoppage of the printing or other machine 11. The mechanism herein described is to automatically correct this condition.

The operation of the mechanisms herein described can probably best be understood by considering a condition requiring the stoppage of the machine 11 during a run of the unit. Under such conditions, power to the motor 18 is interrupted, and power is applied to the motor 37, since, as a matter of economy, it is desirable to utilize the motor 37 only when power to the motor 18 is interrupted, since when power is being derived from the motor 18, no power will be applied to the shaft 22 by the motor 37.

When the motor 18 is stopped and the motor 37 is operated, the actuating mechanism for the carrier 14 will impart continuing travel to said carrier and to the racks 16 carried thereby. As a consequence, the racks 16 will be successively brought into and out of the proper relation to the delivery tapes 17, but no sheets will be delivered thereto. Sheets previously delivered to the oven racks, however, will continue their travel through

the oven, and unnecessary prolongation of the subjection of such sheets to the action of heat within the oven will be avoided.

It will be borne in mind that with the arbitrary figures selected, the frame 30, when the same is operative to apply power to the shaft 22, requires four revolutions to impart one-twenty-fourth of a revolution to the sprocket wheel 15. In other words, four revolutions of said frame is necessary to move one rack 16 out of the proper relation to the tapes 17 and to bring a succeeding rack into such relation.

It will also be borne in mind that the ratio between the gears 31 and 32 is as four to one, and furthermore, that the setting of the parts is such that when the pawl or dog 36 engages the tooth 35, a rack 16 is in the proper position relative to, or in step with, the machine 11, and with the continued operation of the unit, a sheet may be delivered thereto from the tapes 17.

Immediately following the stoppage of the frame 30 and the application of the power of the motor 37 to the shaft 22, irrespective of speed, one of the various racks 16, will begin to pass from this relation or move out of step with the machine 11. At the same time, the gear 32 will impart rotation to the gear 31 to move the tooth 35 out of engaging relation with, and away from, the pawl or dog 36, which movement will be indirect proportion to the quantity of movement of a rack 16 from its proper position in relation to the machine 11. Since it takes four revolutions of the shaft 22 to move one rack 16 from its sheet receiving position and bring the succeeding rack 16 into this position, and since the ratio of the gear 32 to the gear 31 is as one to four, it is obvious that with four revolutions of the shaft 22, the gear 31 will receive one complete revolution, the pawl or dog 36 will again be engaged with the tooth 35, and that this will occur simultaneously with a succeeding rack 16 coming into its proper and normal relation to the machine 11.

Consequently, since the shaft 22, during the normal operation of the unit, has four revolutions to one revolution or cycle of the printing couple 12-13, the operation of the synchronizing attachment of the transmission mechanism, is such as to correct only such error or loss of adjustment in the setting of the carrier mechanism in relation to the printing couple as may occur during one cycle of operations of the printing couple, and error cannot accumulate beyond this.

The carrier 14 may be actuated for any desired length of time after the stoppage of the machine 11, and the conditions will be merely a repetition of the action of the racks 16 out of, and back into, step with the printing couple during a time interval represented

only by that required for one revolution of the members of said couple.

When the conditions are such that the machine 11 may be re-started, it is merely necessary to apply power to the motor 18 irrespective of the relative position of the members 12-13 of the printing couple, or of racks 16 in relation thereto.

For purposes of explanation, it will be assumed that when the machine was stopped, the members 12-13 of the printing couple were in that position selected as the basis of the setting of the various mechanisms during their assembly, or had been brought to that position prior to such application of power, that the shaft 22 had just completed three revolutions following the disengagement of the tooth 35 with the pawl or dog 36, that the power to the motor 37 had been interrupted and the shaft 22 was at rest. Hence, at this moment, the shaft 22 has had three of the possible four revolutions necessary for moving one rack out of its proper position in relation to the machine 11 and a succeeding rack into that position, the gear 31 has received three-quarters of a full revolution, or three-quarters of its possible movement between the disengagement of the tooth 35 and pawl or dog 36 and the re-engagement of these parts, and a rack 16 has been advanced three-quarters of its full movement.

With the application of power to the printing couple of the machine 11, the shaft 28 will be rotated, the frame 30 and the gear 31 turning therewith. Since the gear 32 is idle, the planetary movement of the gear 31 about same will result in its being rotated about its own axis and in a direction opposite to that at which it is rotated by the gear 32 when the shaft 22 is being turned by the motor 37. During this action there will be no clutch action of the gears 31 and 32 to transmit power to the shaft 22.

Upon the completion of each planetary cycle of the gear 31, it will have received a reverse rotary movement of one-quarter of its full revolution, so that it will require three revolutions of the frame 30 before the tooth 35 is again engaged with the pawl or dog 36. Instantly, with the engagement of said tooth and pawl or dog, rotary movement of the gear 31 about its own axis will cease, power will be applied therethrough to the gear 32 as a result of the clutch action thus developed, and the shaft 22 will be rotated at the same speed as the shaft 28. This will occur when the members 12-13 of the printing couple have reached the three-quarter point of their cycle of operations, and will bring the machine 11 into step with the carrier 14, so that during the remaining one-quarter of the cycle, the actuating mechanism for the carrier 14 will be operated to impart the remaining one-quarter of the full movement required to bring a rack into the

proper sheet receiving relation to the tapes 17. In other words, the automatically acting clutch so functions that if any rack 16 has been advanced beyond the point where it is properly set in relation to the position of the printing couple, the actuation of the carrier actuating mechanism will be delayed to the same extent as the rack has been advanced, and will become operative immediately that the relative position of the members 12-13 of the printing couple and of a rack 16 coincides with the normal operating condition for which the unit was initially set, and the extent of the delay will be immediately proportioned to the extent of the advance of the racks, irrespective of the amount of this advance.

If a rack be advanced, or out of step with the machine, only one-quarter of its full movement, the gear 31 will have been actuated to move the tooth 35 only 90° from the pawl or dog 36 and only one revolution of the frame 30 will be required to reestablish the proper setting of the rack in relation to the printing couple.

The rectification of the conditions in the unit will be secured in exactly the same way, irrespective of how much or how little the rack movement is out of step with the machine 11 as determined by the extent of advance of the racks, it being always understood that when the tooth 35 is engaged with the pawl or dog 36, the racks are in step with the printing couple whatever the position in a cycle of operations may be.

It is necessary, to a clear understanding of the operation of the herein described unit, to realize that the degree to which the racks may be out of step is determined by the position occupied by the printing couple 12-13 at the time when a run of the unit begins and is not dependent upon any particular position of said printing couple.

The sheet receiving position of the racks in relation to the delivery tapes is no factor whatever, since a rack may be in this position and be entirely out of step with the printing couple. The racks, under normal conditions, are in step with the printing couple throughout the entire cycle of the couple, and lose step therewith only upon the stoppage of the printing couple and irrespective of the point of such stoppage. If the printing couple has completed one-half of its cycle when it is stopped, a rack will have been advanced one-half of its full movement beyond the tapes 17. If the independent application of power, following this stoppage, is interrupted when the gear 31 has received two of its four possible revolutions, the racks will be out of step with the printing couple in an amount equaling one-half of the full movement of the racks with each cycle of said couple. Hence, at this instant, a rack will be in sheet receiv-

ing relation to the tapes 17 and the shaft 22 will be at rest.

It takes one-half a revolution to complete the cycle of the printing couple. During this one-half revolution, the frame 30 will receive two complete revolutions. With these two complete revolutions, the gear 31 will receive one-half a reverse revolution before the tooth 35 engages the pawl or dog 36. Consequently, at this moment, the machine 11 and the racks 16 are brought into step with each other.

Since the degree to which the racks are out of step with the printing couple is determined by the extent of movement of the tooth 35 away from the pawl or dog 36, and since the position of the frame 30 is determined by the position of the members of the printing couple at any time, the rotation of the gear 31 in the manner above described, to cause movement of the tooth 35 toward the pawl or dog 36 to the same extent that said tooth was moved away from said dog by the gear 32, will establish the same condition of parts as when the printing couple was stopped.

The racks being out of step with the printing couple results from movement of the tooth 35 away from the pawl or dog 36 as a result of the rotation of the shaft 22. The re-establishment of the normal setting of the machine with the racks in step with the printing couple results from the return of said tooth into engagement with said pawl or dog 36.

While I have referred to the position of the printing couple when the machine 11 is first stopped, it is obvious that the same conditions exist even though power be applied to turn the members of the printing couple in either direction while the carrier is being actuated by the motor 37, since this actuation will merely change the position of the members of the printing couple and the frame 30, the relation of the gears 31 and 32 to each other, and the degree to which the racks are out of step.

While it never requires more than one revolution of the printing couple 12-13 to establish a proper relation of the racks therewith, it is obvious that ordinarily this couple is rotated a number of times following each stoppage of the machine before sheets are fed thereto. This condition permits a departure from the exact construction herein described, wherein the arrangement is such that only one revolution of the printing couple is necessary to accomplish the purposes of the invention.

When the clutch mechanism 39 is used, its effect is merely to disconnect the shaft 22 from the motor 37 substantially simultaneously with the application of power to said shaft through the clutch mechanism transmitting power thereto from the shaft 28.

While I have described the invention in

connection with a printing machine and a drying oven, it is obvious that it may be utilized in connection with other machine units in which it is necessary to normally maintain the different mechanisms of the unit in step, one with the other, and in which one of these mechanisms is subject to operation independently of the other.

It is therefore not my intention to limit the invention to the precise details of construction herein shown and described, since such may be varied without departing from the spirit and scope of the invention.

Having described the invention, what I claim as new and desire to have protected by Letters Patent, is:—

1. A drying oven unit embodying therein the combination with a printing or other machine, an oven carrier having a sequence of racks, actuating mechanisms operative respectively upon said machine and said carrier, and a source of power common to both of said actuating mechanisms, of power transmitting means between said mechanisms, embodying therein an automatically acting clutch mechanism permitting the operation of said carrier actuating mechanism independently of said transmitting mechanism, and means whereby said clutch is operative to transmit power only when said machine and said carrier are in normally operative relative positions, and means for applying power to said carrier actuating mechanism independently of said main source of power.

2. A drying oven unit embodying therein the combination with a printing or other machine, an oven carrier having a sequence of racks, an actuating mechanism for said printing machine, and a source of power operative upon said actuating mechanism, of a carrier actuating mechanism containing speed reducing means, whereby said racks are successively advanced by said carrier in timed relation to succeeding cycles of said machine, when said machine and said carrier are in normal operative relation, power transmitting means between said machine and said carrier actuating mechanism, embodying therein an automatically acting clutch mechanism containing a driving member, connections between same and said machine actuating mechanism, a driven member operative upon said carrier actuating mechanism, and means whereby said clutch is operative to transmit power only when said machine and said carrier are in normal operative relative positions, and means for applying power to said carrier actuating mechanism independently of said transmission mechanism.

3. A drying oven unit embodying therein the combination with a printing or other machine, an oven carrier having a sequence of racks, an actuating mechanism for said printing or other machine, and a source of power operative upon said actuating mechanism, of

- a driving shaft, connections between said driving shaft and said machine actuating mechanism rotating said shaft at a higher speed than said machine, differential gearing actuated by said driving shaft, a carrier actuating mechanism including a driven shaft, a gear thereon forming a part of said differential gearing, and connections between said driven shaft and said carrier, an independent source of power operative upon said carrier actuating mechanism including a driven shaft, a gear thereon forming a part of said differential gearing, and connections between said driven shaft and said carrier, an independent source of power operative upon said carrier actuating mechanism, and means operative upon said differential gearing to cause the transmission of power therethrough only when said machine and said carrier are in normal operative relative positions, and permit the application of power to said carrier actuating mechanism from said independent source. 4. A drying oven unit embodying therein the combination with a printing or other machine, an oven carrier having a sequence of racks, an actuating mechanism for said printing or other machine, and a source of power operative upon said actuating mechanism, of a driving shaft, connections between said driving shaft and said machine actuating mechanism rotating said shaft at a higher speed than said machine, a frame carried by and rotatable with said driving shaft, a planet gear mounted in said frame, a carrier actuating mechanism including a driven shaft mounted in said frame, a gear thereon enmeshed with said planet gear, and connections between said driven shaft and said carrier, an independent source of power operative upon said carrier actuating mechanism, and means operative upon said planet gear preventing its rotation and causing the transmission of power therethrough from said driving to said driven shaft when said machine and said carrier are in normal operative relative positions, and permitting its rotation when said driving shaft is inoperative to transmit power, and power is applied to said carrier actuating mechanism from said independent source. 5. A drying oven unit embodying therein the combination with a printing or other machine, an oven carrier having a sequence of racks, an actuating mechanism for said printing or other machine, and a source of power operative upon said actuating mechanism, of a driving shaft, connections between said driving shaft and said machine actuating mechanism rotating said shaft at a higher speed than said machine, a frame carried by and rotatable with said driving shaft, a planet gear mounted in said frame, a carrier actuating mechanism including a driven shaft mounted in said frame, a gear thereon enmeshed with said planet gear, and connections between said driven shaft and said carrier, an independent source of power operative upon said carrier actuating mechanism, a clutch disk having a single tooth carried by and rotatable with said planet gear, and a pawl carried by said frame and co-operating with said tooth, said tooth and said pawl being so positioned that when they are engaged to prevent rotation of said gear and cause the transmission of power therethrough from said driving to said driven shaft, said machine and said carrier will be in normal operative relative positions, and said gear may be moved to disengage said tooth from said pawl when said driving shaft is inoperative to transmit power, and power is applied to said carrier actuating mechanism from said independent source. 6. A drying oven unit embodying therein the combination with a printing or other machine, an oven carrier having a sequence of racks, an actuating mechanism for said printing or other machine, and a source of power operative upon said actuating mechanism, of a driving shaft, connections between said driving shaft and said machine actuating mechanism rotating said shaft at a higher speed than said machine, differential gearing actuated by said driving shaft, a carrier actuating mechanism including a driven shaft, a gear thereon forming a part of said differential gearing, and speed reducing means whereby said racks are successively advanced by said carrier in timed relation to succeeding cycles of said machine, when said machine and said carrier are in normal operative relation, an independent source of power operative upon said carrier actuating mechanism, and means operative upon said differential gearing to cause the transmission of power therethrough only when said machine and said carrier are in normal operative relative positions, and permit the application of power to said carrier actuating mechanism from said independent source. 7. A drying oven unit embodying therein the combination with a printing or other machine, an oven carrier having a sequence of racks, an actuating mechanism for said printing or other machine, and a source of power operative upon said actuating mechanism, of a driving shaft, connections between said driving shaft and said machine actuating mechanism rotating said shaft at a higher speed than said machine, a frame carried by and rotatable with said driving shaft, a planet gear mounted in said frame, a carrier actuating mechanism including a driven shaft mounted in said frame, a gear thereon enmeshed with said planet gear, and speed reducing means between said driven shaft and said carrier, whereby said racks are successively advanced by said carrier in timed relation to succeeding cycles of said machine, when said machine and said carrier are in normal operative relation, an independent source of power operative upon said carrier actuating mechanism, and means operative upon said planet gear preventing

its rotation and causing the transmission of power therethrough from said driving to said driven shaft when said machine and said carrier are in normal operative relative 5 positions, and permitting its rotation when said driving shaft is inoperative to transmit power, and power is applied to said carrier actuating mechanism from said independent source.

10 8. A drying oven unit embodying therein the combination with a printing or other machine, an oven carrier having a sequence of racks, an actuating mechanism for said printing or other machine, and a source of power 15 operative upon said actuating mechanism, of a driving shaft, connections between said driving shaft and said machine actuating mechanism rotating said shaft at a higher speed than said machine, a frame carried by 20 and rotatable with said driving shaft, a planet gear mounted in said frame, a carrier actuating mechanism including a driven shaft mounted in said frame, a gear thereon enmeshed with said planet gear, and speed 25 reducing means between said driven shaft and said carrier, whereby said racks are successively advanced by said carrier in timed relation to succeeding cycles of said machine, when said machine and said carrier are in 30 normal operative relation, an independent source of power operative upon said carrier actuating mechanism, a clutch disk having a single tooth carried by and rotatable with 35 said planet gear, and a pawl carried by said frame and co-operating with said tooth, said tooth and said pawl being so positioned that when they are engaged to prevent rotation of said gear and cause the transmission of power therethrough from said driving to said 40 driven shaft, said machine and said carrier will be in normal operative relative positions, and said gear may be moved to disengage said tooth from said pawl when said driving shaft is inoperative to transmit power, and power 45 is applied to said carrier actuating mechanism from said independent source.

9. A drying oven unit embodying therein the combination with a printing or other machine, an oven carrier having a sequence of 50 racks, an actuating mechanism for said printing or other machine, and a source of power operative upon said actuating mechanism, of a driving shaft, connections between said driving shaft and said machine actuating mechanism rotating said shaft at a higher speed than said machine, a frame carried by 55 and rotatable with said driving shaft, a planet gear mounted in said frame, a carrier actuating mechanism including a driven shaft mounted in said frame, a gear thereon enmeshed with said planet gear, the diameters of said planet gear and said gear enmeshed therewith being in inverse ratio to the speed 60 relation between said machine and said driving shaft, and speed reducing means between said driven shaft and said carrier, whereby said racks are successively advanced by said carrier in timed relation to succeeding cycles of said machine, when said machine and said carrier are in normal operative relation, an independent source of power operative upon said carrier actuating mechanism, and means operative upon said planet gear preventing its rotation and causing the transmission of power therethrough from said driving to said 65 driven shaft when said machine and said carrier are in normal operative relative positions, and permitting its rotation when said driving shaft is inoperative to transmit power, and power is applied to said carrier actuating mechanism from said independent source.

driven shaft and said carrier, an independent source of power operative upon said carrier actuating mechanism, and means operative upon said planet gear preventing its rotation and causing the transmission of power therethrough from said driving to said driven shaft when said machine and said carrier are in normal operative relative positions, and permitting its rotation when said driving shaft is inoperative to transmit power, and power is applied to said carrier actuating mechanism from said independent source.

10. A drying oven unit embodying therein the combination with a printing or other machine, an oven carrier having a sequence of racks, an actuating mechanism for said printing or other machine, and a source of power operative upon said actuating mechanism, of a driving shaft, connections between said driving shaft and said machine actuating mechanism rotating said shaft at a higher speed than said machine, a frame carried by 80 and rotatable with said driving shaft, a planet gear mounted in said frame, a carrier actuating mechanism including a driven shaft mounted in said frame, a gear thereon enmeshed with said planet gear, the diameters of said planet gear and said gear enmeshed therewith being in inverse ratio to the speed 85 relation between said machine and said driving shaft, and speed reducing means between said driven shaft and said carrier, whereby said racks are successively advanced by said carrier in timed relation to succeeding cycles of said machine, when said machine and said carrier are in normal operative relation, an independent source of power operative upon said carrier actuating mechanism, and means operative upon said planet gear preventing its rotation and causing the transmission of power therethrough from said driving to said driven shaft when said machine and said carrier are in normal operative relative positions, and permitting its rotation when said driving shaft is inoperative to transmit power, and power is applied to said carrier actuating mechanism from said independent source.

In witness whereof I have hereunto affixed my signature, this 3rd day of December, 1928.

JOHN D. ELDER.
